(57) **CLAIM**

The ornamental design for a holster cover, as shown and described.

DESCRIPTION

FIG. 1 is a perspective view of a design for a holster cover in accordance with my new design;

FIG. 2 is a top view thereof;

FIG. 3 is a front view thereof;

FIG. 4 is left side view thereof;

FIG. 5 is a right side view thereof;

FIG. 6 is a rear view thereof;

FIG. 7 is a bottom view thereof;

FIG. 8 is bottom perspective view thereof, from the bottom rear; and,

FIG. 9 is an auxiliary view thereof, from the left side showing the holster cover on a holster and a holstered pistol.

The broken lines immediately adjacent the shaded areas represent the bounds of the claim, and all other broken lines are for illustrative purposes only. None of the broken lines form a part of the claimed design.
